UNITED STATES PATENT OFFICE.

HUGH J. FINN, OF KANSAS CITY, MISSOURI, ASSIGNOR TO SULZBERGER & SONS COMPANY, OF CHICAGO, ILLINOIS, A CORPORATION OF NEW YORK.

APPARATUS FOR TREATING HAMS, SHOULDERS, OR JOINT-MEAT IN GENERAL.

1,209,276.

Specification of Letters Patent. Patented Dec. 19, 1916.

Application filed May 1, 1916. Serial No. 94,826.

To all whom it may concern:

Be it known that I, HUGH J. FINN, of Kansas City, in the county of Jackson and State of Missouri, have invented certain new 5 and useful Improvements in Apparatus for Treating Hams, Shoulders, or Joint-Meat in General, of which the following is a specification.

This invention relates to apparatus for 10 pressing hams to produce "square" hams, so-called, or, in other words, to mold a ham to provide it with a plurality of rectangular faces.

There is a large and growing demand in 15 the trade for cooked hams intended to be cut into a plurality of thin slices for ultimate consumption. Hams are naturally of irregular form and in order that they may be sliced to the best advantage to avoid 20 waste it is desirable that the hams be given a predetermined and rectangular form. This is particularly true where the hams are sliced by machines of which there are now numerous examples on the market.

25 It is an object, therefore, of my invention to provide means of simple construction which may be readily operated by unskilled labor to mold hams to provide a plurality of rectangular faces thereon.

30 A further object of my invention is the provision of means for subjecting a ham to pressure to re-distribute the fatty portions thereof, whereby the ham is given a more even texture and waste of the valuable food 35 constituents thereof is prevented.

A further object of my invention is the provision of means for shaping a ham to a predetermined form, whereby the ham may be thoroughly cooked in a shorter period 40 than would be required if it was left in its natural state.

A still further object of my invention is the provision of means for treating hams to cause the parts which are necessarily separated in removing the bone to adhere, whereby 45 subsequent separation during the slicing is effectually prevented.

Further objects and advantages of my invention will be apparent as it is better understood by reference to the following specification when read in connection with the accompanying drawing, illustrating the preferred embodiment thereof, in which

50 Figure 1 is a side elevation of an apparatus according to my invention; Fig. 2 is an

end elevation thereof; Fig. 3 is an enlarged transverse section on the line 3—3 of Fig. 1; Fig. 4 is an enlarged detail in perspective of the mold and means for applying pressure to the sides thereof; Fig. 5 is a detail in perspective of the removable side-plate of the pressure-applying means, and Fig. 6 is a detail in perspective of the pressure plate to transfer pressure to the top of the mold.

In carrying out my invention the ham is 65 first boned in the usual manner, is wrapped, preferably in a textile material to prevent disintegration and inserted in the mold presently to be described. The ham is then subjected to pressure to cause it to assume 70 the form of the mold, the fatty portions being simultaneously re-distributed by pressure. The top and sides of the mold are secured to retain the ham in its compressed form and the ham is cooked while still in 75 the mold for the desired period. When the cooking has been completed the ham may be removed from the mold and will be found to have permanently assumed the form there- 80 of so that it may be readily sliced either manually or in a suitable machine.

Referring to the drawing, 1 indicates a suitable base to which a pair of uprights 2 are secured. A member 3 is secured to the uprights 2 and supports a pair of screws 4 85 extending downwardly, and having suitable hand wheels 5, to apply pressure, as will presently appear.

Mounted on the base 1 is a bed 6 having a side plate 7 integral therewith or secured thereto. A loose side-plate 8 is adapted to be disposed opposite the side-plate 7, the side plates 7 and 8 being embraced by the clamping members 9 pivotally secured at 10 to the bed 6. Screws 10' are mounted in the 90 clamping members 9 to provide means for forcing the movable side plate 8 toward the side-plate 7.

A mold comprising the bottom 11 and sides 12 formed integral therewith is adapt- 100 ed to be mounted on the bed 6 between the side plates 7 and 8, a movable top 13 being disposed between the sides 12 of the mold. A pressure plate 14, adapted to receive the thrust of the screws 4 is disposed above the 105 top 13 and transfers pressure thereto. The sides 12 of the mold are provided with a plurality of aligned holes 15 through which bolts 16 having wing-nuts 17 on their ends may be selectively disposed to lock the sides 110

12 and the top 13 in position after the material within the mold has been compressed. The pressure plate 14 is provided with slots 18 in its under face and the side-plates 7 and 8 are provided with suitable openings 19 to facilitate the insertion of the bolts 16.

The mode of operation of my invention will be readily apparent from the following brief description thereof: The boned ham 20 is wrapped and disposed within the mold which is arranged between the side-plates 7 and 8. The top 13 is inserted and the pressure plate 14 is disposed thereabove after which the screws 4 and 10' are actuated to apply pressure to the sides 12 in the top 13 of the mold. The result is that the ham 20 is forced to assume the form of the mold and is thereby provided with rectangular sides. The ends of the mold are held by the wrapping and material elongation of the ham is prevented. Incidentally the fatty portion of the ham is re-distributed about and through the fibrous portion. When the ham has been suitably compressed the bolts 16 are inserted in suitable holes 15 to lock the sides 12 and top 13 of the mold in position. The screws 4 and 10' are released, the mold is withdrawn and the ham is cooked for a suitable period in its compressed condition.

Obviously a plurality of molds must be provided to allow rapid operation and these molds may be of various sizes to accommodate hams of different weight. It will be understood, moreover, that while I have described my invention particularly with respect to hams it is equally applicable to the treatment of shoulders or joint meat in general.

Meat treated in the manner described, after being cooked, permanently assumes the form of the mold and may be sliced without waste. Consequently my invention fills a long-felt requirement of the trade and accomplishes definite and useful results, the product resulting from the use of my invention being distinguished from similar products heretofore known in the art.

It will be apparent that various changes may be made in the form, construction and arrangement of the parts without departing from the spirit and scope of the invention, or sacrificing any of its material advantages, the form hereinbefore described being merely a preferred embodiment thereof.

I claim:

1. In an apparatus of the character described, the combination of a mold having a bottom and yielding sides, open ends and a removable top, and means for applying pressure to said sides and top.

2. In an apparatus of the character described, the combination of a mold having a bottom and integral sides, a removable top, means for applying pressure to said sides

and top, and means for securing said top and sides in position when the material within said mold has been compressed.

3. In an apparatus of the character described, the combination of a mold having a bottom and integral sides, a removable top, means for applying pressure to said sides and top, said sides being provided with a plurality of aligned holes, and bolts for securing said top and sides in position when the material within said mold has been compressed.

4. In an apparatus of the character described, the combination of a mold having a bottom and integral sides, a removable top, clamping members embracing said mold for applying pressure to said sides, means for applying pressure to said top, and means for securing said top and sides in position when the material within said mold has been compressed.

5. In an apparatus of the character described, the combination of a mold having a bottom and integral sides, a removable top, clamping members embracing said mold for applying pressure to said sides, a pressure plate adapted to engage said top, means for applying pressure to said plate, said sides being provided with a plurality of aligned openings, and bolts adapted to engage said openings to secure said top in position when the material within said mold has been compressed, said pressure plate having grooves on its under side to allow the insertion of said bolts.

6. In an apparatus of the character described, the combination of a bed, a side plate rigid therewith, a movable side plate, a mold comprising a bottom, integral sides and a removable top adapted to be mounted on said bed, clamping means secured to said bed for applying pressure to said movable side plate and the sides of said mold, a pressure plate adapted to rest on the top of said mold, and means associated with said bed for applying pressure to said pressure plate.

7. In an apparatus of the character described, the combination of a bed, a side plate rigid therewith, a movable side plate, a mold comprising a bottom, integral sides and a removable top adapted to be mounted on said bed, clamping means secured to said bed for applying pressure to said movable side plate and the sides of said mold, a pressure plate adapted to rest on the top of said mold, means associated with said bed for applying pressure to said pressure plate, and means for securing the sides and top of said mold when the material therein has been compressed.

8. In an apparatus of the character described, the combination of a bed, a side plate rigid therewith, a movable side plate, a mold comprising a bottom, integral sides and a removable top adapted to be mounted

- on said bed, clamping means secured to said bed for applying pressure to said movable side plate and the sides of said mold, a pressure plate adapted to rest on the top of said mold, means associated with said bed for applying pressure to said pressure plate, the sides of said mold being provided with a plurality of alined holes, and bolts engaging said holes for securing the top and sides 10 of said mold when the material therein has been subjected to pressure.
9. In an apparatus of the character described, the combination of a bed, a side plate rigid therewith, a movable side-plate, 15 a mold comprising a bottom, integral sides and a removable top adapted to be mounted on said bed, clamping means secured to said bed for applying pressure to said movable side-plate and the sides of said mold, a pressure plate adapted to rest on the top of said mold, means associated with said bed for

applying pressure to said pressure plate, the sides of said molds being provided with a plurality of alined holes, and bolts engaging said holes for securing the top and sides of 25 said molds when the material therein has been subjected to pressure, said side-plates being provided with openings through which said bolts may be inserted in said holes.

10. In an apparatus of the character described, a mold having a bottom and sides integral therewith, a removable top, said sides being provided with a plurality of alined holes, and bolts adapted to selectively 30 engage said holes to secure said top and sides in place.
